UNITED STATES PATENT OFFICE.

HERBERT E. WILLIAMSON, OF SAN FRANCISCO, CALIFORNIA.

GEARING.

1,148,881.

Specification of Letters Patent.

Patented Aug. 3, 1915.

Application filed February 14, 1914. Serial No. 818,797.

To all whom it may concern:

Be it known that I, HERBERT E. WILLIAMSON, a citizen of the United States, residing at San Francisco, in the county of San Francisco and State of California, have invented new and useful Improvements in Gearing, of which the following is a specification.

The object of the present invention is to provide a steam washing machine for domestic use which will be simple of construction, and of low cost, capable of being operated by a small motor, which will be under the complete control of the user and which will be very effective in its operation.

In the accompanying drawing, Figure 1 is a perspective view of the machine; Fig. 2 is an enlarged broken vertical section thereof; Fig. 3 is a broken inside view of one end of the tank; Fig. 4 is an enlarged broken vertical section of the machine; Fig. 5 is a sectional view, showing in elevation the inner side of the other end of the tank; Fig. 6 is a side view of a cam; Fig. 7 is a side view, and Fig. 8 an edge view, of a rotator ring.

Referring to the drawing, 1 indicates a rectangular hollow box-like body, closed at the top by a removable cover 2, and open at the bottom and supported upon legs 3, adapted to travel upon casters 4. Within said body, but depending below its bottom, is a closed iron tank 6, which is drained by a pipe 7 closed by a valve 11, loosely hinged at the top, as shown at 9, and having on its outer side a rib 8 which is adapted to be engaged by the middle portion of a yoke 12 to press the valve down to its seat, said yoke being raised by a rod 13, the upper portion of which extends through a guide 14 upon an end of the body. When said rod is so raised the yoke abuts against a lug 16 projecting from the valve, and raises the valve from its seat.

To the under side of the tank is secured an eye 17 adapted to be engaged by a hook 18 upon an end of a gas burner tube 19, the other end of which is adapted to be connected to a flexible tube, not shown, leading to a gas supply pipe. Said other end has a hook 21 which extends upwardly through an eye 22 secured upon the adjacent end of the tank and removably held in place by a pin 23.

Within the tank is a clothes cylinder 24, the cylindrical side of which is formed of woven wire material 26, a portion thereof being omitted to form an opening by which

the clothes can be inserted into, and removed from, the cylinder. In said cylinder are radially extending ribs 27, secured to the ends 28 of the cylinder. Said opening is closed by a door 29, also cylindrical in form and made of woven wire material, and secured by lugs 33 adapted to engage keepers 32 on the ends of the cylinder. The lugs have arms 34 projecting outside the door by which they can be raised from their keepers.

On one end of the cylinder is secured a gear wheel 36 and from said gear wheel and from the other end of the cylinder extend centrally trunnions 37. The trunnion on said other end is adapted to rest in a bearing 38 secured on the inner surface of the corresponding end of the tank, and open at the top, so that the cylinder can be raised therefrom, while the other trunnion is guided by jaws 39 secured to the other end of the tank and converging downwardly toward a fixed support 41 on said inner end. Between said support and jaws can move the ends of fingers of a bifurcated lever 42, pivoted on the inner side of the corresponding end of the tank, of which one end is connected to an end of a link 47, the other end of which is connected to the free end of a crank arm 43 on a shaft 46 passing through the adjacent end of the tank and body, and having on the outer end a hand lever 44 by which it can be turned. By turning this hand lever the adjacent trunnion of the cylinder can be moved horizontally to the right or left as desired.

When moved in one direction the gear wheel 36 on said cylinder is in mesh with a small pin wheel 49 on a shaft 51 extending through the adjacent ends of the tank and body and rotating in a bracket 52 and carrying a wheel 53 having a deep groove 54 therein. Frictionally engaging an inner side of said groove is a cone 56 on a shaft 57 rotating in a bearing 58 supported upon said bracket and having secured thereon a pulley 59 with a deep groove 61. In said groove is a belt 62 extending from the shaft of a motor 63 secured upon a leg of the machine. By means of said motor, and by the frictional engagement of said cone 56 with said wheel 53, the cylinder is rotated within the tank, and the water in the tank is thereby caused to pass through the clothes in the cylinder and wash the same. However, I provide means whereby, after a predetermined number of rotations in either direc-

tion of the cylinder 24, this direction of motion is reversed. Such means operate as follows:—To the gear wheel 36 is secured a pin 64, which, once in each rotation of the cylinder, is adapted to engage an arm 66 of a number, here shown as three, of arms on a shaft 67 rotating in a tube 68 extending through the adjacent ends of the tank and body.

- 10 Secured to the shaft 67, within said tube 68, is a ring 69, from the periphery of which extends outwardly, in a direction parallel with the shaft 67, a lug 71, two similar rings 72 loose on the shaft having similarly extending lugs 73, the last lug 73 extending in a groove 74 in a disk 76 loose on the shaft. The periphery of said disk is formed at opposite sides with cam surfaces 77, (Fig. 6) which engage the ends of arms 78 extending 15 from a shifter 79 pivoted at the bottom, as shown at 81, to the bracket 52, so that, as the disk is turned, said shifter is rocked. In said shifter is a loose bearing 82 for the shaft 57 of the friction cone, and springs 83 20 on opposite sides of the bearing 82 are compressed between said bearing and the ends of the shifter. When the shifter is thus rocked, the friction cone moves out of contact with one side of the groove in the wheel 53 and into contact with the other side of 25 said groove, and, the shaft 57 being rotated from the motor constantly in one direction only, the motion of the shifter causes the grooved wheel 53 to be rotated in the opposite direction to its previous direction. Hence, with each nine rotations of the 30 clothes cylinder, the direction of its rotation is reversed automatically. For, with each rotation, the pin 64 rotates the shaft 67 35 through one-third of a rotation and with one rotation of the shaft, the lug 71 of the first ring engages the lug 73 of the second ring and causes it to revolve with it, so that in three rotations of the shaft 67 or nine rotations of the cylinder the last lug 73 reaches 40 the end of the groove 74 causing the disk 76 to rotate and actuating the shifter 79. It may be reversed voluntarily by moving 45 a rocking lever 84 pivoted on the body and pivoted to a link 86 the other end of which is pivoted to said disk. Or the motion of the clothes cylinder can be brought to rest by moving said rocking lever 84 to a central 50 position, thereby causing the shifter to assume a central position, so that the friction cone makes a driving contact with neither 55 wall of the groove of the wheel 53.
- On the shaft 51 is a loose sleeve 87, having notches 88 in its side, which can be engaged by pins 89 extending outwardly from the adjacent hub of the grooved wheel 53. Said sleeve is moved longitudinally along said shaft 51 by forks extending from the lower end of a lever 91 pivoted at 92 upon 60 an arm 93 extending outwardly from the ad-

jacent end of the body 1. When the upper end of said lever is moved toward said body, the lower end is moved toward said wheel 53, and said lugs are caused to engage the sleeve 87, imparting rotation thereto 70 from the rotation of the shaft 51. On said sleeve is a sprocket wheel 94 which is engaged by a sprocket chain 96 which also engages a sprocket wheel 97 on the shaft 99 of the lower roller 101 of a wringer 102 having 75 also an upper roller 103, said wringer being permanently secured upon the adjacent side of the body 1. The direction of operation of the wringer can, like that of the clothes cylinder, be reversed by suitably actuating 80 the lever 14.

To use the wringer a lever 91 is actuated to cause the sleeve 87 to rotate with the shaft 51.

I claim:—

1. The combination of a shaft, an element rotated thereby, an extension from said element, a gear wheel secured to said element, a pinion meshing with said wheel, a shaft carrying said pinion, a motor, a shaft rotated thereby, an operative connection between said latter shaft and the first-named shaft, a fourth shaft, arms carried thereby adapted to be actuated by said extension, and means actuated by said fourth shaft to 95 reverse the direction of the first-named shaft.

2. The combination of a shaft, an element rotated thereby, an extension from said element, a second shaft, an operative connection between said second shaft and element for rotating the latter, a motor shaft, an operative connection between said motor shaft and the second-named shaft, a fourth shaft, arms carried thereby adapted to be actuated 100 by said extension, and means actuated by said fourth shaft to reverse the direction of the first-named shaft.

3. The combination of a rotatable element, an extension from said element, a gear wheel secured to said element, a pinion meshing with said wheel, a shaft carrying said pinion, a motor, a motor shaft rotated thereby, an operative connection between said motor shaft and the first-named shaft, 110 a shaft, arms carried thereby adapted to be actuated by said extension, a series of rings on said last-named shaft each having a lug on its periphery arranged to engage a lug on an adjacent ring, a shifter for changing the 115 direction of rotation of the first-named shaft and means actuated by said last-named ring for actuating said shifter.

4. The combination of a rotatable element, a shaft for rotating said element, a 125 wheel on said shaft having a deep groove, a motor, a shaft driven thereby, a cone thereon arranged to frictionally engage either side of said groove, a movable bearing for said last-named shaft, means for shifting 130

said last-named shaft, and means actuated with a predetermined number of rotations of the rotatable element for actuating said shifting means.

5 5. The combination of a rotatable element, a shaft for rotating said element, a wheel on said shaft having a deep groove, a motor, a shaft driven thereby, a cone thereon arranged to frictionally engage either
10 side of said groove, a spring-controlled movable bearing for said last-named shaft, means for shifting said last-named shaft and means actuated with a predetermined number of rotations of the rotatable ele-
15 ment for actuating said shifting means.

6. The combination of supporting means, a rotatable element having at its end trun-

nions, a support at one end of said supporting means for one of the trunnions, a guide for said trunnion leading to said support, a shaft extending through said supporting means, devices on said shaft and element adapted to engage each other and form an operative connection from said shaft to said element, and means extending through said supporting means for moving said trunnion on said support to form said connection.

In testimony whereof I have hereunto set my hand in the presence of two subscribing witnesses.
